UNITED STATES PATENT OFFICE.

EDWARD C. NEWCOMB, OF SCITUATE, MASSACHUSETTS, ASSIGNOR TO STANDARD ENGINEERING COMPANY, OF ST. LOUIS, MISSOURI, A CORPORATION OF MISSOURI.

EXHAUST-STEAM TURBINE.

1,331,999.

Specification of Letters Patent. Patented Feb. 24, 1920.

Application filed June 30, 1919. Serial No. 307,696.

To all whom it may concern:

Be it known that I, EDWARD C. NEWCOMB, a citizen of the United States, residing in the town of Scituate and county of Plymouth and State of Massachusetts, have invented new and useful Improvements in Exhaust-Steam Turbines, of which the following is a specification.

This invention relates to steam turbines 10 of the type designed to be operated by the exhaust steam from a steam engine.

The broad idea of my invention consists in providing an exhaust-steam-actuated turbine with automatic means for increasing 15 the nozzle area as the volume of the exhaust steam increases, thereby keeping the steam velocity approximately constant, irrespective of variations in steam volume.

The embodiment of the invention shown 20 in the drawings is particularly adapted for use on a steam automobile for driving the fan which draws in air through the radiator, which latter acts as a condenser for the steam from the engine.

Attempts have been made to use an exhaust steam turbine for the purpose contemplated in the present invention, but due 25 to the fact that the turbine has been directly connected to the fan, and that the nozzle area was constant, so much back pressure was produced in the turbine that it materially reduced the power of the engine.

It is well known that the load on the engine of an automobile is constantly changing, depending, among other things, upon 35 whether the car is running up hill, or down hill, or at a high or low rate of speed, and upon the manner of control of the throttle by the operator. It will, therefore, be obvious that to get the best results from a turbine which is run by the exhaust steam of an engine that is constantly changing load, it is necessary that a construction of 40 turbine be employed that will adapt itself 45 to such changing conditions.

Due to the construction and principle of operation employed in my turbine, as hereinafter more fully indicated, I am enabled 50 to secure the maximum efficiency from the steam without increasing the back pressure on the engine.

In the adaptation of my invention as an

exhaust turbine for steam automobiles, the exhaust pipe from the engine is connected to the turbine intake, and the discharge 55 from the turbine is connected to the top of the radiator, and the steam passing through the radiator is condensed to water and returned to the water tank, which latter is supported by the frame of the car and is 60 below the bottom of the radiator. As stated, the turbine runs a fan for drawing air through the radiator, or condenser, so as to increase the efficiency of said radiator in condensing the steam back to water. 65

While I have thus briefly indicated the general purpose and principle of operation of my invention in its embodiment in an exhaust turbine for steam automobiles, I 70 wish it distinctly understood that the invention is not limited to such adaptation, and that the broad underlying principle of operation is useful in other adaptations and in other types of turbines.

In the accompanying drawings illustrating the invention:

Figure 1 is a view in side elevation of a turbine constructed according to my invention:

Fig. 2 is a vertical transverse sectional view thereof taken on the line 2-2 of Fig. 3;

Fig. 3 is a view partly in side elevation and partly in section looking at the turbine from the rear, or from the right as it is 85 shown in Fig. 1;

Fig. 4 is a cross-sectional view taken on the line 4-4 of Fig. 2;

Fig. 5 is also a cross-sectional view taken on the line 5-5 of Fig. 2 and viewed in 90 the direction of the arrows;

Fig. 6 is a developed sectional view on the curved line 6-6 of Fig. 4; and

Fig. 7 is a detailed perspective view illustrating one of the automatically adjustable 95 gate valves for controlling the area of the nozzle of the turbine.

Referring now to the drawings, the numerals 1, 2, respectively, indicate the two halves of the cylindrical wall of the turbine, and 3, 4, the end plates thereof, the cylinder walls and end plates being correspondingly apertured at two or more points to receive tie-bolts 5, which prevent move-

ment between the two parts of the cylinder and which, with other bolts, 6, connecting the end plates and located outside of the cylinder wall, serve to hold the cylinder 5 and end plates in assembled relation. The numeral 7 indicates the turbine shaft which is surrounded at its outer end portions by bushings 8, and is journaled at one end in a bearing 9 provided centrally of the end plate 10 4. At its opposite end this shaft extends through a sleeve bearing 10 in the end plate 3 and has secured on such projecting end a pulley 11, over which a belt runs, as usual, for driving the fan, neither of which 15 is shown. The numeral 12 indicates the hub of the turbine wheel, or rotor, which is keyed on the shaft 7 and is connected by spokes 13 to a rim 14. The rim 14 is circumferentially recessed at regular intervals to 20 receive studs 15 on the bottom edges of the turbine blade 16, said studs being welded, or otherwise firmly secured in the said rim. A band ring 17 is shrunk about the outer 25 ends of the blades 16, and forms the outer engaging surface of the rotor with the inner wall of the cylinder 2. Each section 1, 2 of the cylinder has cast integral with it an interior annular wall, indicated, respectively, by the numerals 18 and 19, which 30 walls are shaped to provide opposed circumferential portions 20 between which the rim 14 is slidably received, and which walls constitute the side walls of the chamber in which the blades 16 rotate (see particularly 35 Figs. 2 and 6). In their central portions the said walls have a circular enlargement which provides a central chamber 21 which, as shown by Fig. 2, incloses the hub, spokes and rim of the rotor and one wall of which 40 is provided at its bottom with a port 22 to permit of the escape of water of condensation from said chamber, and also to permit entrance of steam to equalize pressure on the rotor. The numeral 23 (Figs. 1 and 2) 45 indicates the inlet for exhaust steam to the turbine which inlet is located in the bottom portion of the end plate 4. This inlet receives exhaust steam from the engine and conducts it into a chamber 24 located between the wall 19 and the end plate 4 (see 50 Figs. 2, 4, and 6). In Fig. 4 the relative position of the inlet 23 is indicated by the dotted circle 23. The bottom of the wall 19 is made relatively thick and in this portion of the wall a port 25, indicated by dotted lines in Fig. 2 and shown in Figs. 4 and 6, is formed and provides access of the steam from the chamber 24 to the blade 16 of the rotor. This port is circularly elongated, and, roughly speaking, extends about a third-way around the wall 19. Mounted in the 55 chamber 24 is a gate valve 26, which is shown in detail in Fig. 7. This valve is mounted for rotatory movement about the bushing 8

of shaft 7 by means of a hub 27. Said valve 65 comprises an arm 28 projecting radially from the hub 27, and having on its outer edge a flange extension, or head, 29, which is adapted to slide against the inner side of the end plate 4. Extending at right angles 70 to the lower edge of the arm 28 is a segmental plate 30 which is adapted to bear against the polished side of a web 31 (see Figs. 2 and 6) projecting slightly beyond the other face of the wall 19, said web and 75 the wall 4 forming seats for guiding the movement of the valve 26 as a whole. Extending downwardly and inwardly from the arm 28 near the outer end thereof and likewise projecting downwardly from the under 80 side of the plate 30, is an integral valve member 32, the construction of which provides an inclined face 33 constituting one side of the throat or nozzle of the turbine. The valve member 32 is adapted to move in the 85 port 25 in the wall 19, being limited in its movement in one direction by the end of the web 31, and in the other direction by an inclined wall 34 provided at the inner end of the port 25 and extending parallel with the 90 inclined face 33 of the valve member 32. The valve tends normally to be moved to its closed position by a coil spring 35, connected at one end to a lug 36 on the hub 27 of the valve, and at its other end to a pin 95 37 extending through the wall of part 2 of the cylinder, the projecting end of the pin being screw-threaded to receive an adjusting nut 38, by means of which the tension on the 100 spring 35 may be varied as circumstances may require. Opposite the chamber 24 and between the end plate 3 and wall 18 is a similar chamber 39 which communicates with a port 40 in the wall 18 similar to the port 25, said port being controlled by a valve 41 similar in all respects to the valve 26, and mounted in the same manner. The end wall 42 of the port 40 and the inclined side 43 of the valve 41 form, as in the previous 105 case, an expandable and contractible nozzle through which steam may pass to the blades 16 of the rotor. Beyond the valve 26, the wall 19 is provided with an elongated exhaust port 44 (see Figs. 2 and 4) which 110 communicates with a chamber 45, (see Figs. 2 and 6), which in turn communicates with an outlet manifold 46, the latter being adapted to be connected in any suitable way with the radiator as previously indicated.

The operation of the device is as follows: 115
Exhaust steam from the engine enters the inlet 23 to the chamber 24 and passing through the nozzle afforded by the wall 34 of port 25 and the inclined face 33 of the valve member 32, impinges upon and passes between the blades 16 of the rotor, causing the latter to revolve, and enters the chamber 39 on the opposite side of the turbine. 120
125

From the chamber 39 the steam then passes through the nozzle formed by the end wall 42 of port 40 and the inclined face 43 of valve 41, and again impinges upon and 5 passes between the blades of the rotor, passing out through the port 44 into the chamber 45 and thence to the exhaust 46, whence it is conducted to the radiator. According 10 as the volume of steam is greater or less, the position of the valves 26, and 41 will vary. That is to say, using valve 26 as an illustration, as the steam increases in volume the pressure exerted upon the face of the arm 28 and valve member 32 will cause the valve 15 26 to be moved away from the end 34 of port 25, against the resistance of spring 35, to widen the nozzle for the incoming exhaust steam, thereby diminishing its velocity and likewise preventing back pressure upon 20 the engine. As the volume of steam decreases, the coil spring 35 will tend to move the valve 26 toward the wall 34, thereby decreasing the area of the inlet nozzle to the turbine. The same operation occurs, of 25 course, with respect to the valve 41, which latter valve is controlled by a coil spring 47, (Fig. 5). Thus it will be seen that I secure practically constant speed of rotation 30 of the rotor, irrespective of changes in load on the engine, by automatically adjusting the size of the nozzle, or nozzles, of the turbine in accordance with the increase or decrease in volume of steam passing through 35 the turbine. It will readily be seen also that such an arrangement prevents increases 40 in back pressure on the engine as, coincident with increase in volume, and therefore pressure, of the steam, there is a corresponding increase in the size of the path of escape for the steam.

The construction herein illustrated represents the most practical embodiment of my invention now known to me, but the invention may be embodied in a different construction of apparatus without at all departing from the principle of providing a compensating nozzle for steam turbines characterizing the invention.

It will furthermore be apparent that the 50 exhaust steam need not be conducted again through the blades of the rotor after having once passed through them from the port 25, but that the exhaust steam may be passed directly from the chamber 39 to the exhaust 55 manifold 46, and the valve 41 be dispensed with. In other words, the principle of the invention is applicable to a single-acting, as well as to a double-acting turbine.

I claim:

60 1. In an exhaust-steam turbine, in combination with the rotor and means for conducting steam thereto, automatic means for increasing the area of the steam-conducting means as the volume of steam increases.

2. In an exhaust-steam turbine, in combination with the rotor, a nozzle for conducting steam to said rotor, and means for automatically adjusting the area of said nozzle in accordance with the volume of steam admitted thereto to maintain an approximately constant steam velocity. 65 70

3. In an exhaust-steam turbine, in combination with the rotor, means for maintaining an approximately constant steam velocity comprising a compensating nozzle for 75 conducting steam to the rotor.

4. In an exhaust-steam turbine, in combination with the rotor, a nozzle for conducting steam thereto, said nozzle having a movable member adapted to be displaced by 80 increase in volume of the steam passing to said nozzle to increase the area of said nozzle, and means tending normally to move said member to decrease the area of said nozzle. 85

5. In an exhaust-steam turbine, in combination with a rotor chamber, a rotor mounted therein, an elongated port in one wall of said chamber for permitting access of steam to said rotor, and a valve controlling said port and yieldable upon increase in the volume of steam supplied thereto to increase the area of said port. 90

6. In an exhaust-steam turbine, in combination with the rotor chamber, a rotor 95 mounted therein, an elongated port in one wall of said chamber for permitting access of steam to said rotor, a movable, spring-controlled valve governing said port and subject to the pressure of steam supplied thereto, whereby upon increase in the volume of steam said valve will be moved to increase the area of said port to a greater or less extent, and upon decrease in the volume of steam said valve will be moved 100 by its spring to decrease the area of said port to a greater or less extent. 105

7. In an exhaust-steam turbine, in combination with the rotor and nozzles for passing steam through the rotor from opposite directions, automatic means for increasing the area of said nozzles as the volumes of steam supplied thereto respectively increase. 110

8. In an exhaust steam turbine, in combination with a rotor chamber, a rotor 115 mounted therein, ports provided in opposite walls of said chamber for permitting continuous passage of the steam through said rotor in different directions, and a valve controlling each of said ports, said valves 120 being yieldable to increase the area of the respective ports upon increase in the volumes of steam supplied thereto.

9. In an exhaust steam turbine, in combination with the rotor chamber, a rotor 125 mounted therein, an elongated port in one wall of said chamber for permitting access of steam to said rotor, a movable spring con-

trolled valve governing said port and subject to the pressure of steam supplied thereto, whereby upon increase in the volume of steam said valve will be moved to increase 5 the area of said port to a greater or less extent, and upon decrease in the volume of steam said valve will be moved by its spring to decrease the area of said port to a greater or less extent, and means for adjusting the tension of said spring. 10 In testimony whereof I have hereunto set my hand.

EDWARD C. NEWCOMB.
